TRAFFIC SIGNAL

Substitute for application Serial No. 704,671, filed April 7, 1924. This application filed July 26, 1929.
Serial No. 381,340.

This invention relates to an improvement in traffic signals, and with respect to its more specific features to signals to be carried by motor vehicles.

5 An object of the invention is to provide a compact, light-weight signal of the character specified, simple in construction and of pleasing appearance, and capable of displaying on a common field, a selected one or more 10 of a number of different signals or designs, without the use of moving parts.

Another object is to provide a construction wherein the signal indications or designs are made visible, each by light striking 15 at a selected angle, thus to enable the display of the selected design while the other designs are left in darkness.

Another object is to provide a signal having a plurality of designs with parts in common and parts peculiar to each design and with all of the parts in the same plane, each 20 design made visible by light transmitted from a selected angle, to enable the display of a selected design while the parts peculiar to 25 the other design remain in darkness.

Another object is to provide in such a signal, means to distinctively color the light from each of the selected angles during its transmission to the design, thereby to display 30 the designs in distinctive colors.

Another object is to provide in such a signal, having a number of signal indications or designs visible by transmitted light, and means to illuminate a selected indication 35 with light of a distinctive color, a parking lens so arranged that when any indication is illuminated the parking lens will be also illuminated, serving thus as a tell-tale to indicate the functioning of the signal.

40 With this and other objects in view, the invention consists in the construction and novel combination of parts fully described herein-after, illustrated in the accompanying drawings, and pointed out in the appended claims; it being understood that various changes in 45 the form, proportion, size and minor details of construction, within the scope of the claims, may be resorted to without departing from 50 the spirit of the invention.

In the accompanying drawings forming a part hereof;

Figure 1 is a front view of the improved signal, as it appears by reflected light.

Figures 2 and 3 are similar views, with the 55 warning legends displayed.

Figures 4 and 5 are front views, with the turn indications displayed.

Figure 6 is a front view of the back of the casing, with the cover removed.

60 Figure 7 is a rear view of the cover.

Figure 8 is a perspective view of the back of the casing, looking from the front.

Figure 9 is a perspective view of the light screen and ray filter for the speed change 65 indications or warning legends.

Figure 10 is an end view of the back of the casing.

Figure 11 is a similar view of the cover or 70 front, with the light screen and filter for the legends in place.

Figure 12 is a front view of the stencil plate having the speed change indications.

Figure 13 is a perspective view of the plate, 75 looking from the right.

Figure 14 is a similar view, looking from the left.

Figure 15 is a perspective view of the plate, looking from the right and from below.

Figure 16 is a plan view of the blank from 80 which the central screen is formed.

Figure 17 is a plan view of the translucent plate, forming the white reflector for the indications, and the concealing means for the speed change indications or legends.

Figure 18 is a perspective view of the tail light collar, detached from the casing.

Figure 19 is a plan view of the retaining ring.

Figure 20 is a plan view of a light filter 90 for a turn indication.

Figure 21 is an enlarged detail in plan of a part of the stencil plate.

Figure 22 is a front view of the supporting 95 bracket.

Figure 23 is a plan view of a part of the blank forming the bracket.

Figure 24 is a perspective view of the bracket and back with the cover removed. 100

Figure 25 is a front view of the stencil plate for the front signal.

Figure 26 is a perspective view of the ray filter for the same, used for the display field.

Figure 27 is a diagrammatic view of the wiring for the signal.

In the present invention I provide a traffic signal for indicating to the drivers of other vehicles, traffic officers and the like, the intentions of the driver of the car, as to stopping, changes in direction and the like, the signal indications being so arranged that they stand out vividly by transmitted light, and sundry of the indications by reflected light, especially designed for the rear of a car, but capable with minor changes for use at the front, and I also provide means whereby the signal indications at the front and rear may be simultaneously controlled to display like indications. In the embodiment of the invention shown, a casing is provided, composed of shells 1 and 2, the former a back or body and the latter a front or cover, and the flanges of the shells fit one within the other to form the side walls of the casing. The shells are of suitable sheet material, cut and stamped or otherwise brought to shape, and they cooperate with certain transparent or translucent sheets and lenses to form a closed receptacle, which is supported by a bracket plate of heavier material.

The bracket plate, by means of which the casing is connected to a car and to a license plate, comprises a body portion 3, having lateral extensions 4, longitudinally slotted at 5 for receiving bolts to connect the license plate to the bracket and the bracket to the car, and the said extensions are at the bottom of the bracket. At each side edge of the bracket body flanges 6 and 6^a extend forwardly, and the flanges extend well above the top of the body as shown.

Each flange has an inwardly extending lug 7 at its top, and a pair of outwardly extending lugs 8 and 8^a, intermediate its ends, and the corresponding lugs of the pairs are in register. The flange 6 has another lug 9, extending outwardly and upwardly above the lug 5, and the extremity thereof is parallel with the flange. The ends of the lugs 8^a are thickened or reinforced by bending over the extremity of the lug upon the body, for a purpose to be presently described, and all of the lugs are formed from the material of the flanges. Thus openings are provided through the flanges at the lugs.

The back or body is deeply notched at its lower edge, the notches spaced apart a distance corresponding to the distance between the flanges of the bracket, and these notches receive the flanges, the back being slipped down in front of the bracket body, until the top wall or flange rests upon the lugs 7. The lower wall or flange is engaged beneath the

lugs 8^a and the said lugs and the lugs 7 lock the back tightly to the bracket.

Each flange 6 and 6^a has an opening near its upper end, one of which, that in the flange 6, gives passage to an electric light socket 10, while that in the flange 6^a affords an attachment for a socket 10^a. The socket 10 is supported by the lug 9, and the sockets hold bulbs 11 and 11^a. The bulbs are in a compartment formed by the casing walls, the flanges 6 and 6^a, and a partition plate 12, extending transversely between the flanges, and supported thereby. The partition plate has angular end portions which fit the inner faces of the flanges above the plate and are secured thereto by screws 12^a.

The casing is divided into three compartments by the partition 12 above mentioned, and a partition 12' arranged below the partition 12, and the bulbs 11 and 11^a are in the upper compartment. The ends of the partition plate 14 are bent downwardly at an angle to the body, as shown at 15 and 15^a, to form supports for sockets 14^a, holding bulbs 16 and 16^a, which extend through the openings of the flanges formed by the bending of the lugs 8, 8^a and 9.

It will be noticed, referring to Figure 1, that the casing as a whole is roughly oblong in shape, and may be considered as comprising a body, the space between the flanges 6 and 6^a, and wings, comprising the spaces in the ends outside the wings. Since these end spaces or chambers communicate with the middle compartment through the openings in the bracket flanges, the central compartment is of greater length than the upper and lower compartments.

The lower compartment contains a bulb 19, held in a socket 18, which is supported by the end 15 of the plate 14, and this source of light is designed to serve as a tail light, and to illuminate the license plate, which is directly below it. A frame 20 closes the bottom of the casing, and the lower compartment, and the frame carries three sheets of transparent material, a central sheet 21, and lateral sheets 22 and 22^a, which are set at an angle to the sheet 21. The sheets, which may be of any suitable material, as for instance glass or celluloid, are of different color, the sheet 21 white, the sheet 22 green, and the sheet 22^a red. The sheets 22 and 22^a provide colored side lights, and the flanges 6 and 6^a have circular openings in line with the sheets for transmitting the light.

The ends 15 and 15^a of the partition 14, and the ends of the frame 20 have lapping flanges 15^b which fit against the flanges 6 and 6^a, and are secured thereto by screws 14^b, to hold the plate and frame in proper position.

The flange of the cover fits outside of the flange of the back or body, and the parts are connected by screw bolts 24 to the lugs 7 and 8^a. Preferably the openings for the screw

bolts at the lugs 8^a for the cover are notches instead of openings, so that the cover can be slipped away from the bolts when they are loosened.

5 The cover 2 has a display opening at its top, which is closed by a translucent sheet 25, which by reflected light is white, and a stencil plate 26 is held just behind the sheet. The cover has also certain cutouts, forming signal indications at the middle compartment, and it has a circular opening 27 at the lower compartment, which is closed by a lens 26, colored red, and serving as a tail light when illuminated.

15 Referring to Figures 7, 18 and 19, it will be seen that the cover has a collar 29, held in the opening 27, and that the lower edges of the sheet 25 and the stencil plate are recessed at 30 and 31, respectively, to receive the collar. The collar has radial openings 32 suitably spaced, and the stencil plate has perforated lugs 33 registering with the radial openings, when the stencil plate is properly placed in the cover. A split ring 34 fits with-
25 in the collar, and the ring has radial lugs 35 which engage the openings of the collar and those of the lugs 33, to lock the parts together. The stencil plate is then held in the proper relation to the display opening 2^a, and by contracting the split ring the parts may be separated.

35 The stencil plate is roughly diamond shaped, and is arranged on the inner face of the sheet 25, which being translucent hides the stencil plate until the casing is illuminated from within. The plate is of thin sheet material, to reduce the shadows cast by the edges of the cut-outs to be described, and the upper edge of the plate, and the side edges of
40 the inclined sides are flanged, as indicated at 36 and 37 respectively, to reinforce and strengthen the plate.

45 The plate has cut-outs 38, 39 and 39^a, at the middle compartment, the cutouts 39 and 39^a of arrow-head or spear-head shape, and spaced apart from each other, being in fact outside the flanges 6 and 6^a of the bracket. They are symmetrically arranged, with the points of the arrow-heads outward, and the 50 cut-out 38 is between them, forming the body or shaft of the arrow. Each of the heads forms with the shaft a signal indication, the shaft being common to both indications.

55 At the display opening 2^a, and in the upper compartment of the casing, the stencil plate has cutouts, sundry of which cooperate with sundry of the others to form a plurality of warning legends or signal indications, and 60 the legends or indications have parts in common. Referring to Figure 12, it will be seen that there is a cutout 40 forming the letter S, a plurality of cutouts 41 forming the letter O, and another plurality forming the letter P. The letters S and O are common to the

two legends, while the letter P is peculiar to one of the two.

In addition to the cutouts above mentioned, there are others, some peculiar to the letter L, and some peculiar to the letter T, and some common to both letters. The letter L is formed by cutouts 45, 46, 47 and 48, the first and the last two cooperating with another cutout 49 to form the letter T. In addition to the cutouts forming the letters S and O, the cutouts 45, 47 and 48 are common to both legends. 75

Since the letter P is peculiar to one legend, and is always shown in one color, red in the present instance, it is covered by a plate 50 of transparent material of the proper color, but means in the form of ray filters and light screens is provided to direct the light from the respective sources 11, 11^a, 16 and 16^a, to the parts or cutouts of the appropriate signal or indication, while excluding it from the parts or cutouts peculiar to the other signal or indication, and for imparting to the light a distinctive color. 80

85 The said means for the sources 11 and 11^a, includes screens 51, 52, 53 and 54, the first 90 51 serving as a screen for the letter P, and it is arranged at the inner side of the cutouts forming the letter, and near the adjacent side of the letter O. The screen 52 is inverted L-shape, and is designed to screen the cutout 49, when the legend Slo is displayed, it being understood that in the present instance the legends Slo and Stop are used. The screen 53 is designed to screen the cutout 46 when the legend Stop is displayed, and the screen 54 is designed to screen the cutout 46 in the same circumstances. 95

100 The screens are secured to the stencil plate, near the cutouts which they are intended to screen, and each has a non-reflecting face adjacent to the said cutout. The face away from the cutout is reflecting, that is white, and the plane of each screen is in the line connecting the axis of the screen with the 105 source of light with which it does not cooperate in its screening function. The plane of each screen is at a reflecting angle to the rays from the source with which it does cooperate in its screening function. The arrangement is such that the rays from the source 11 will have an unrestricted passage through the cutouts forming the legend Slo, while the rays from the source 11^a will have an 110 unrestricted passage through the cutouts forming the legend Stop. 115

120 The plate 50 over the cutout 42 serves also as a screen, when the legend Slo is displayed, for the letter P, and as a reflector and absorber for the light from the source 11^a, to insure that the letter P will be invisible when the legend Slo is displayed. 125

125 The ray or color filter for the sources 11 and 11^a, to provide distinctive colors for the legends, in the present instance green for 130

Slo and red for Stop, is shown in Figures 7, 9 and 11. It is composed of two vertically spaced plates 57 and 58, connected at their angles by fins 59, 60 and 60^a, all of which extend in the same direction, the fin 59 between the fins 60 and 60^a. When the filter is in place, the fin 59 is substantially perpendicular to the stencil plate, but the fins 60 and 60^a are inclined inwardly toward the fin 59.

Sheets 61 and 62 of transparent or translucent material are held by the plates between the fins, and the two sheets, which in the present instance are red and green respectively, close the two short faces of the casing formed by plates 57 and 58, and by the sheets. The sheets are held in place by clips or lugs 63 on the plates, and adjacent to each is a light limiting screen or shield 64, for restricting the amount of light passing through the sheet.

The open side of face of the casing comprising the light filter is positioned against the rear face of the stencil plate, covering all of the cutouts except that forming the letter P, and it is held in place by a bolt and nut 65. The bolt passes through an opening 66 in the flange 36 of the stencil plate, and through a registering opening in the plate 57. The parts are so arranged that the light sources 11 and 11^a are directly behind the sheets 61 and 62, and between the fins. Thus the light rays from the respective sources are directed through the appropriate filters to provide green light for the legend Slo, and red light for the legend Stop.

The ray or light filters for the sources 16 and 16^a in the middle compartment are in the form of sheets 67 and 68 of transparent or translucent material, the former colored green in the present instance and the latter red. As shown in Figure 20, each sheet has lugs 69 at its upper edge, which engage openings in the body portion of the partition 12, and the lower edge of each has a rounded notch 70 which fits over the adjacent socket 14^a. The sheets are arranged at an angle of about forty five degrees to the plane of the stencil plate, and substantially perpendicular to the light rays from the adjacent source. Thus the sheets are at an angle to each other of about ninety degrees, and each serves as a reflector for the rays from the remote source, and as a transmitter for the rays from the adjacent source. Each is of an area such that no white light from the adjacent source may strike the parts of the signal indications in the compartment. The sheets 67 and 68 are arranged across the openings formed in the flanges 6 and 6^a by the bending of the lugs 8, 8^a and 9.

A parking light lens 72 is held in an opening in the cover between the upper and middle compartments, and in such position that the light from either compartment may pass through it. That is the lens is partly above

and partly below the partition 12. A portion 73 of the partition at the lens is struck out from remainder, and bent downward at an angle towards the back of the casing, so that there is a free passage for the light from above or below the partition. When any indication, either legend or arrow, is illuminated, the parking light lens will be illuminated with light of a like color, in the present instance, green for Slo or right turn, and red for Stop or left turn.

Since the heads of the arrows or arrow indications are always illuminated with the same color, sheets 74 and 75 of transparent or translucent material are held over the openings in the stencil plate which form the head indications. The color of illumination for the shaft of the arrow indications depends upon which of the head indications is illuminated, since the shaft must be in like color, and the sheets 67 and 68 are depended upon to impart the distinctive color to the rays from the appropriate source.

The frame 20 rests at its rear edge on a flange 76 at the lower edge of the back or body, and it has a hood 77 depending from the front thereof, rounded and flanged to engage within the cover, it being understood that the lower edge of the cover between the flanges 6 and 6^a of the bracket plate extends straight down to provide room for the frame.

In Figure 16 the blank from which the screens 52 and 54 are formed is shown. The portion of the blank forming the screen 52 is inverted L-shape, and screens the stem and one arm of the T, and the blank has a lateral extension forming the screen 54 for the cutout 48. The blank after bending to shape is connected to that portion of the material of the stencil plate which is partly separated from the plate to make the cutout for the body of the letter L. The connection is made by means of struck up lugs 80 on the portion 81 engaging openings in the blank, and bent to hold the parts together.

The bracket plate is deeply notched as shown at 79 in Figure 23, between the body and each wing, to receive the edge of the back, thus to lock the parts together more firmly, and they are further secured together by a bushing 80^a which passes through registering openings in the bracket and back respectively, and is held by a nut 83 inside the casing. The openings are indicated at 81 and 82, and the bushing gives passage to the cable carrying the electrical connections to be described.

The lugs 33 of the stencil plate are bent through the notches 78 in the collar, and are then bent down on the inner face of the collar, to hold the parts more firmly, and to prevent angular movement of the stencil plate.

When the shield 73 is bent back upon the partition 14, or cut away, the shaft 38 of the

arrow or turn indication is illuminated from the upper compartment, and becomes an underscore in white for the legends Stop and Slo. The light from the upper compartment, 5 when either legend is illuminated is sufficiently strong to display the shaft, but not strong enough to illuminate the cutouts 39 and 39^a.

The changes necessary in the adaptation of 10 the improved signal for use as a front signal are shown in Figures 26 and 25, it being understood however that the signal as described may be used as a front signal without change, if desired. Since the legends Slo and Stop 15 serve no purpose at the front, they are omitted in the adaptation unless for any reason it is desired to retain them.

Referring to these figures it will be seen 20 that the stencil plate for the front signal, indicated at 85 has a display field or opening 86, of approximately the same size as the opening 2^a, and similarly placed. In addition it has cutouts 87, 89 and 90, corresponding 25 to the cutouts 39 and 39^a, and of the same shape. This plate takes the place of plate 26, so that instead of displaying legends, the front signal displays in the upper compartment fields of color, green and red, in the present instance, when the rear signal displays Slo and Stop in like colors.

The combined filter and screen in the upper compartment, to distinctively color the light, is similar in shape to that of the rear signal, previously described, except that it 35 is larger, large enough in fact to cover the entire display field, and to screen it from any light but that passing through colored sheets 95 and 96. The filter and screen is composed of the upper and lower plates 91 and 92, connected by the three fins 93 and 94, and the 40 sheets 95 and 96.

In order to provide a telltale which will indicate that the signal is functioning properly, and that the signal displayed is that intended to be displayed, the fin 93 may be made V-shaped or branched, the branches indicated at 93^a and 93^b in Figure 26, and each branch has an opening over which is held a sheet 97 5 and 98 of transparent or translucent material, colored to correspond with the adjacent sheet 95 or 96 as the case may be.

With this arrangement, the light from the source 11 will be colored by the sheet 97 before it reaches the telltale lens, and the lens will be illuminated in green in the present instance. In like manner the light from source 11^a will be colored red by the sheet 97, and the lens will appear in like color.

50 All of the light sources are electrically controlled, deriving current from either the storage battery 100 or the magneto 101. They may be controlled manually by a suitable switch arranged convenient to the driver's hand, as for instance on the steering wheel, or

they may be controlled by the movement of certain mechanisms of the car on which the signals are carried, as for instance, the steering mechanism or the brake or clutch pedal. In the latter case switches are provided which are operated, either directly or indirectly, by the movement of the steering wheel in turning, and by the brake or clutch pedal in the performance of its functions. The last mentioned control is automatic, the steering wheel 75 controlling the turn indication display, while the pedal controls the display of the legends. 76

The wiring including the switches is shown 80 diagrammatically in Figure 27, wherein a panel 104 is provided for the instrument board, carrying means in the form of switches for connecting the light sources in circuit with either source of energy 100, 101, with an electrically controlled audible signal 109, with either or both of the switches of the automatic control, or with the manual control switch, as may be desired.

The switches 105, 106, 107 and 108, on the panel 104, are composed each of a switch arm and two contact buttons, and the three last named are off and on, or cutout switches. The arms of the switch 105—106 and the on button of switch 108 are connected to the arm 113 of the manually operated switch to be described, by a lead wire 112, 126 and 129. 90

The light sources of the corresponding indications of the front and rear signals are connected in parallel to be simultaneously illuminated, and one terminal of each source is grounded, so that the current flows from the source of energy through the light source and to ground. The other terminals of the sources at front and rear are connected by lead wires 121, 122, 123, and 124, the wires connecting the sources of corresponding indications of the two signals. 95

Another lead wire 125 connects the ungrounded terminals of the light sources 19, and a wire 127 connects the on button of switch 107 with the ungrounded terminal of the audible signal 109, which may be a horn or buzzer. The arrangement of the circuits 121 to 125 inclusive, is the same, and such that when current is delivered to the wire between the sources, a part thereof will flow through each source, the sources of each wire being thus in parallel. A lead wire 125 connects the on button of switch 106 with the wire 125, and lead wires 110 and 111 connect the respective buttons of switch 105 with the storage battery 100 and the magneto 101. 110

The arms of switches 102 and 103 are connected to the arm of switch 108 by lead wires 130 and 131 respectively, and the buttons of switch 102 are connected by lead wires 132 and 133 with the circuits 123 and 122 respectively. A like service is performed for the buttons of switch 103 and the circuits 121 and 125, by lead wires 132^a and 133^a. The switch 103 is designed for control by the steering 115 120 125 130

gear of the car on which the signal is used, and the said switch controls the display of the right and left turn indications. The switch 102 is designed for control by the brake or clutch pedal, and controls the display of the indications Slo and Stop.

The manual control comprises the arm 113 and contact buttons 114, 115, 116, 116^a, 117, 118, 119 and 120. The arm is so constructed, and the buttons are so arranged, that contact may be made with certain pairs of selected buttons. Thus the arm may engage simultaneously buttons 115 and 116, or buttons 117 and 118. The buttons 114 and 115 are connected by a common lead wire 134 with circuit 121. The buttons 116, 116^a and 117 are connected by a common lead wire 135 with circuit 122. The buttons 118 and 119 are connected by a common lead wire 136 with the circuit 124, and the button 120 is connected by a wire 137 to the circuit 123.

Premising that the switch 105 is arranged to connect one of the sources of energy to the arm 113 of the manual control, the said arm will make connections with the circuits as follows:

On the button 114, with circuit 121 to display the left turn indications; on buttons 115 and 116, with circuits 121 and 122 to display the left turn indication and the legend Slo; on button 116^a, with circuit 122 to display the legend Slo; on buttons 117 and 118, with circuit 122 and 124, to display the right turn indication and the legend Slo; on button 119, with circuit 124 to display the right turn indication, and on button 120 with circuit 123 to display the legend Stop.

By means of the switches on the panel 104, the system may be connected up in the manner desired; to take current from either source; to include or leave out the audible signal, and to operate automatically or manually. When operated automatically, slowing for a turn will display the legend Slo, and the movement of the steering wheel to make the turn will display the right or left turn indication, in accordance with the direction the wheel is turned. This arrangement is of especial utility where the attention of the driver must be centered on the driving, as for instance in city streets, or wherever the traffic is heavy.

When a front signal is used the field thereof will display green and red when the rear signal displays Slo and Stop respectively, and the turn indications will correspond with those displayed by the rear signal. The same signal might be used in front as is used in the rear, but the legends are unnecessary, and are preferably omitted.

Taken as a whole the signal is of pleasing appearance, and may be mounted on the car wherever desired, or where required by the regulations of the State in which the car is licensed. The colors in which the indications are displayed may also be made to conform

to regulations. Where colors other than green and red are required, they will be used. Transparent or translucent sheets of the color required will be substituted for those of green and red. The sheet 21 above the license plate may likewise be made to conform with regulations, as may also the sidelights.

One of the distinctive features of the improved signal is the absence of moving parts. Everything is fixed and stable. Another is the use of bulbs of plain glass, to be obtained anywhere in case of breakage. Another is the easy adaptation of the signal to color requirements, and the minor changes required to adapt the signal for front or rear use.

The legends and the turn indications have in common, that in each there is a plurality of designs on a common field, and with parts common to both designs, the arrow shaft for the turn indications, and the letters S and O for the legends; that the several designs are displayed by light striking from different angles; and that all are displayed by light from a selected direction, that is from within the casing.

The sheet of translucent material between the stencil plate and the front or cover conceals the designs by reflected light, it being obvious that were there any object to be gained by doing so, the cutouts for the turn indications might be in the stencil plate, so far as concerns distinctive characteristics, the cover of the casing having merely a display field through which the indications would appear.

The circuit wires for the sources are collected into a cable or cables, indicated at 140, which passes through the bushing to the switch board.

What I claim as new is:

1. In a traffic signal, a stencil plate having cutouts cooperating in groups to form letters for a plurality of words, sundry of the groups constituting letters common to all the words, another of the groups having parts cooperating to form independent letters each of which is peculiar to one of the words, and sundry of the parts being common to both letters, a source of light for each word, the sources positioned to illuminate the plate from different angles, means to distinctively color the light from each source, and means in connection with the plate for screening the parts peculiar to each word when the source pertaining to the other word is illuminated, said means including light filters opaque to the color of the light from said other source.

2. In a traffic signal, a stencil plate having cutouts cooperating in groups to form letters for two words, sundry of the groups cooperating to form single letters common to both words, another group having parts cooperating to form two letters each peculiar to one of the words and with sundry of the parts common to the two letters, a source of light

for each word, the sources positioned to illuminate the plate with light from different angles, and screens arranged adjacent to selected parts of the last named group to shadow said parts against light coming from one of the sources, and means to distinctively color the light from each source, including differently colored sheets of transparent material, the sheets between the sources and the plate and held at an angle with respect to each other, such that each will serve as a reflector for light passing through the other.

3. In a traffic signal, a stencil having cutouts cooperating in groups to form letters for two words, sundry of which letters are common to both words and others peculiar to each word, a source of light for each word, the sources positioned to illuminate the stencil from different angles, means to screen the cutouts of each of the last named letters from light transmitted by the source pertaining to the other word, and means to distinctively color the light from each source, including differently colored sheets of transparent material, each supported between a source and the stencil, and a frame in which the sheets are held positioned against the stencil and forming therewith and with the sheets a closed chamber, said sheets held at an angle to each other, such that each sheet reflects the light from the other source.

4. In a traffic signal, a stencil plate having cutouts cooperating in groups to form the letters of two words, a source of light for each word, the sources positioned to illuminate the plate from different angles, screens to shadow sundry of the cutouts from illumination by one source thereby to enable the words to be displayed in alternation, and means to distinctively color the light from each source, including differently colored transparent sheets one arranged between each source and the plate, and supported at substantially an angle with respect to each other, such that one will reflect the light transmitted by the other.

5. In a traffic signal, a stencil plate having cutouts cooperating in groups to form the letters of two words, a source of light for each word, the sources positioned to illuminate the plate from different angles, screens to shadow sundry of the cutouts from illumination by one source thereby to enable the words to be displayed in alternation, and means to distinctively color the light from each source, including differently colored transparent sheets one arranged between each source and the plate, and supported at substantially an angle with respect to each other, such that one will reflect the light transmitted by the other, a frame connected with the plate for supporting the sheets and forming with the plate and sheets a closed chamber, the stencil plate having a cutout serving as an underscore for both words and below the

frame thereby to enable the underscore to be illuminated by uncolored light from either source.

6. A traffic signal including a casing having in one wall an opening, a stencil plate for the opening having cutouts cooperating in groups to form two indicating signals, a source of light for each signal, the sources positioned within the casing to illuminate the plate from different angles, screens to shadow one or more of the cutouts from illumination by one source, thereby to enable the indications to be displayed in alternation, means to distinctively color the light from each source, including differently colored transparent sheets one arranged between each source and the plate, and supported at an angle with respect to each other such that one will reflect the light transmitted by the other, a frame connected with the plate for supporting the sheets and forming with the plate and sheets a closed chamber, the casing having a cutout in the opposite wall from the stencil plate to provide a telltale light and within the same chamber thereby to be illuminated in accordance with the signal displayed.

7. In a traffic signal, a casing having cutouts forming two designs with one or more parts in common and one or more parts peculiar to each design, a source of light for each design, the sources positioned to illuminate the cutouts from different angles, and differently colored transparent sheets arranged between the respective sources and the cutouts, each positioned to transmit light to the cutouts from the adjacent source and arranged at an angle to the other sheet such that light transmitted thereby will be reflected toward the cutouts.

8. In a traffic signal, a casing having cutouts forming two designs with parts in common and parts peculiar to each design, a source of light for each design, the sources positioned to illuminate the cutouts from different angles, and differently colored transparent sheets arranged between the respective sources and the cutouts, each positioned to transmit light to the cutouts from the adjacent source and arranged at an angle to the other sheet such that light transmitted thereby will be reflected toward the cutouts, the casing having a cutout forming a telltale adjacent the cutout common to both designs to be illuminated from either source in accordance with the light transmitted through the sheet adjacent thereto.

9. In a device of the class described, a stencil plate having cutouts forming a plurality of words on a common field, a lamp arranged near each end of the plate, each lamp designed to illuminate one word, a frame abutting the plate between the same and the lamps, and sheets of transparent material supported by the frame, each sheet positioned to transmit the light from the ad-

jaçent lamp and to reflect the light from the other lamp, said sheets differently colored to illuminate the words in different colors.

10. In a device of the class described, a stencil plate having cutouts forming a plurality of words on a common field, a lamp arranged near each end of the plate, each lamp designed to illuminate one word, a frame abutting the plate between the same and the lamps, and sheets of transparent material supported by the frame, each sheet positioned to transmit the light from the adjacent lamp and to reflect the light from the other lamp, 15 said sheets differently colored to illuminate the words in different colors, one of the words including cutouts outside of the frame, and a transparent sheet of the same color as the sheet through which light is transmitted to 20 the word covering said cutouts.

11. In a signalling device, a casing having a plurality of compartments, and a plurality of signalling indications in one wall at each compartment visible by transmitted 25 light, means to illuminate any selected indication with light of a distinctive color, a tell-tale indication, and means whereby the illumination of either signal indication will simultaneously illuminate the telltale indication with light of like color.

12. In a device of the class described, a pair of shells, one a back and the other a cover, and fitting one within the other to form a closed casing, and a supporting bracket for 35 the casing, comprising a body engaging the outer face of the back shell and side flanges extending into the casing between the shells and engaging the top and bottom of the casing.

40. 13. In a device of the class described, a pair of shells, one a back and the other a cover, and fitting one within the other to form a closed casing, and a supporting bracket for the casing, comprising a body engaging the outer face of the back shell and side flanges extending into the casing between the shells and engaging the top and bottom of the casing, the ends of the casing spaced apart from the flanges between the top and bottom of 45 the casing.

55. 14. In a device of the class described, a pair of shells, one a back and the other a cover, and fitting one within the other to form a closed casing, and a supporting bracket for the casing, comprising a body engaging the outer face of the back shell and side flanges extending into the casing between the shells and engaging the top and bottom of the casing, the ends of the casing spaced apart from 60 the flanges between the top and bottom of the casing, the flanges having openings at the extensions of the casing.

65. 15. In a device of the class described, a pair of shells, one a back and the other a cover, and fitting one within the other to

form a closed casing, a supporting bracket for the casing, comprising a body engaging the outer face of the back and side flanges extending into the casing between the shells and still engaging the top and bottom of the casing, and partitions extending between the flanges and dividing the casing into an upper, a lower, and a middle compartment, the ends of the casing spaced apart from the flanges between its top and bottom, and the flanges having openings forming communications between the middle compartment and the extensions.

16. In a device of the class described, a pair of shells, one a back and the other a cover and fitting one within the other to form a casing, a supporting bracket for the casing, comprising a body engaging the outer face of the back and side flanges extending into the casing between the shells and engaging the top and bottom thereof, said casing open at the bottom between the flanges, and a frame carrying transparent sheets to close the bottom supported by the flanges.

17. In a device of the class described, a pair of shells, one a back and the other a cover and fitting one within the other to form a casing, a supporting bracket for the casing, comprising a body engaging the outer face of the back and side flanges extending into the casing between the shells and engaging the top and bottom thereof, said casing open at the bottom between the flanges, and a frame carrying a central and lateral transparent sheets supported by the flanges to close the bottom, the lateral sheets inclined to the central sheet to provide side lights when the casing is illuminated, the flanges apertured at the sheets.

18. In a device of the class described, a display front having translucent display fields, and a circular opening for a tail light lens, a collar held in the opening, a stencil plate with designs, and a concealing translucent sheet between the plate and the front, both plate and sheet recessed to receive the collar, a lens seated in the collar, the stencil plate having lugs fitting outside the collar, the lugs and collar having registering openings, and a split ring seated within the collar on the lens and provided with lugs engaging the registering openings.

19. A signalling device including a plurality of words which have certain letters in common and at least one letter in each word peculiar to the said word, said last named letters of the words so arranged that parts thereof are common to both letters, a source of light for each word, said sources arranged to illuminate the words from different angles, and screens to shield the parts of each letter not common to both from the light source which is designed to illuminate the other word, said screens offering no impediment to the passage of light from the other source.

20. In a traffic signal, a stencil plate having cutouts cooperating in groups to form letters for a plurality of words, sundry of the groups constituting letters common to all the words, another of the groups having parts 5 cooperating to form independent letters each of which is peculiar to one of the words, and sundry of the parts being common to both letters, a single source of light for each word, the sources positioned to illuminate the plate from different angles, and means to shield the parts of the last-named group not pertaining to the letter of the selected word from the light of the source not pertaining to the 10 said word.

15. 21. In a signal, in combination, a display field having two distinct signal indications with one or more parts common to both indications and one or more parts individual to 20 one or another of the indications, a source of white light for each signal indication positioned respectively to illuminate said display field from different angles thus to selectively display the indications and differently colored 25 transparent color screens positioned respectively between said light sources and said display field so as to color the light transmitted through the screens from the respective sources to the common parts of said signal indications whereby the latter may be selectively illuminated in different colors by 30 said light sources.

22. In a signal, in combination, a display field having two distinct signal indications 35 with one or more parts common to both indications and one or more parts individual to one or another of the indications, a source of white light for each signal indication positioned respectively to illuminate said display field from different angles thus to selectively display the indications and differently colored 40 transparent color screens positioned respectively between said light sources and said display field so as to color the light transmitted through the screens from the respective sources to the common parts of said signal indications whereby the latter may be selectively illuminated in different colors by said light sources, and another light screen colored similarly to one of the first mentioned 45 color screens and positioned adjacent to one of the individual parts of said signal indications so as to transmit and color the light from one of said sources to said last mentioned individual part.

50. 23. In a signal, in combination, a casing having a display field provided with two distinct direction indications including a part common to both indications and a directing 55 part individual to each indication, a source of light for displaying each direction indication and means including differently colored light screens, one positioned between each said source and the display field, and through 60 which the rays from said sources are respec-

tively transmitted for selectively displaying the said common part of said direction indication in different colors.

24. In a signal, in combination, a casing having a display field provided with two distinct direction indications including a part common to both indications and a directing part individual to each indication, a source of light for displaying each direction indication and means including differently colored light screens one positioned between each said source and the display field and through which the rays from said sources are respectively transmitted for selectively displaying the said common part of said direction indication in different colors, and an individual transparent color screen for each of said directing parts of the respective direction indications.

25. In a signal, in combination, a display field having two distinct signal indications with one or more parts common to both indications and one or more parts individual to one or another of the indications, a source of light for each signal indication positioned respectively to illuminate said display field from different angles thus to selectively display the indications, differently colored transparent color screens positioned to transmit light from the respective sources to the common parts of said signal indications whereby the latter may be selectively illuminated in different colors by said light sources, and an individual transparent color screen for one of said individual parts of the signal indications, one of said first mentioned color screens being angularly positioned with reference to the display field and having one end positioned adjacent said last mentioned screen and substantially intermediate the latter screen and the adjacent common part of 100 said signal indication.

26. In a signal, in combination, a display field having a plurality of words each with at least one letter peculiar thereto, said peculiar letters occupying the same letter space on the display field, said peculiar letters having a part common to both and parts individual to each, a source of light for illuminating each word, each source positioned so that direct light rays therefrom will illuminate all the letters of the respective words, and baffles to shield the individual parts of said peculiar letters of each word from the light rays emanating from the source of light for the other word but being positioned substantially parallel to light rays emanating from the other source so as to offer no obstruction to the passage thereof to the display field.

27. In a signal, in combination, a display field having a plurality of words each with at least one letter peculiar thereto, said peculiar letters occupying the same letter space on the display field, a source of light for illuminating each word, each source positioned so that 125

direct light rays emanating therefrom will illuminate all of the letters of the respective words, and means to prevent direct light rays from the source for each word from illuminating the said peculiar letter for another word.

28. In a signal, in combination, a display field having a plurality of words each with at least one letter peculiar thereto, said peculiar letters occupying the same letter space on the display field, said peculiar letters having a part common to both and parts individual to each, a source of light for illuminating each word, each source positioned so that direct light rays emanating therefrom will illuminate all the letters of the respective words, each said source positioned so that light rays emanating therefrom will fall at an oblique angle upon the letter space occupied by said peculiar letters and flat baffle plates to shield the individual parts of said peculiar letters of each word from the light rays emanating from the source of light for the other word, the planes of the said baffle plates for shielding the individual parts of one peculiar letter being disposed substantially at the oblique angle of the rays from the source for illuminating the other peculiar letter.

29. In a signal, in combination, a display field for displaying signal indications, a plurality of light sources spaced apart and each positioned for illuminating said display field, a translucent color screen for each light source, each positioned to transmit light rays emanating from one source to said display field, said color screens having flat surfaces angularly related to said display field and with the light rays from the respective source such that light rays from each source passing through one color screen may impinge upon the adjacent flat surface of the other color screen and be reflected thereby to illuminate said display field.

30. In a signal, in combination, a display field for displaying signal indications, a plurality of light sources spaced apart and each positioned for illuminating said display field, a translucent color screen for each light source, each positioned to transmit light rays emanating from one source to said display field, said color screens having flat surfaces angularly related to said display field and with the light rays from the respective source such that light rays from each source passing through one color screen may impinge upon the adjacent flat surface of the other color screen and be reflected thereby to illuminate said display field, and said color screens being of complementary colors so that light rays colored by one screen will not readily pass through the other screen.

31. In a signal, in combination, a casing having a display field for displaying signal indications, means to selectively illuminate said display field in distinctive colors, a telltale indication mounted on said casing and

means whereby the illumination of said display field in a selected color will simultaneously illuminate the telltale indication in the same color.

Signed at Washington, District of Columbia, this 25th day of July, A. D. 1929.

EDWARD COOPER TAYLOR.
